UNITED STATES PATENT OFFICE.

HENRY PEZZETTI, OF PHILADELPHIA, PENNSYLVANIA.

STREET-SWEEPER.

1,085,475.

Specification of Letters Patent.

Patented Jan. 27, 1914.

Application filed December 14, 1912. Serial No. 736,709.

To all whom it may concern:

Be it known that I, HENRY PEZZETTI, a subject of the King of Italy, having declared my intention to become a citizen of the United States, residing in Philadelphia, in the county of Philadelphia and State of Pennsylvania, have invented certain new and useful Improvements in Street-Sweepers, of which the following is a specification.

10 The principal objects of the present invention are to provide a comparatively simple, reliable and efficient self-loading dust-proof street sweeper which shall, to a large extent, be automatic in operation and which can be 15 readily dumped and otherwise manipulated and controlled from the operator's seat.

The invention will be claimed at the end hereof, but will be first described in connection with the embodiment of it chosen for 20 illustration in the accompanying drawings, in which—

Figure 1, is an elevational view, partly in section, of one side of the sweeper. Fig. 2, is a similar view of the other side of the 25 sweeper, showing the parts in somewhat different positions. Fig. 3, is a top or plan view of the sweeper. Fig. 4, is a transverse sectional view of the same. Fig. 5, is a detail view looking toward the front from the 30 position of the broom. Fig. 6 is a sectional view taken on the line 6—6, of Fig. 5, and Fig. 7, is a sectional view taken on the line 7—7, of Fig. 5.

The sweeper may be self-propelled or 35 drawn by horses or mules and for the sake of description the latter type of machine has been selected.

1, are the side pieces shown as angle irons which with appropriate end pieces make up 40 the frame of the machine, and the frame is mounted on suitable wheels 2 and 3.

4 is a revolving broom that is arranged between the front and rear wheels 3 and 2 and it is disposed cross-wise of the frame and at 45 right angles to the line of draft. In front of the broom there is a comb 5, the separate teeth of which are yielding or springy so that they normally receive the sweepings from the broom and yet may spring upward and 50 pass over any obstruction. This is shown in Fig. 5.

6, is an endless apron which receives the sweepings from the broom and comb and conveys them into the boot or housing 7 of an elevator 8. The boot or housing of this elevator is carried by the frame 1 and ex-

tends upward between the front and rear wheels and terminates in a movable chute 9 that discharges into the closed body 10. The elevator conveys the sweepings upward and 60 discharges them from the chute 9 into the body 10. The body 10 is or may be of the self-dumping variety and when it is dumped the sweepings are deposited. The broom 4 is revolvably mounted between the arms of a 65 yoke 11, and the yoke 11 is pivoted by arms 12 to the side pieces 1. The yoke is connected by a link 13 to an arm 14 on a shaft pivotally-carried by the frame and provided with an arm 15 to which is attached a chain 70 16 that is connected with a lever 18 by means of which lever and connections, the driver may raise and lower the broom. The guide wheels 19 which carry the hood 20 and also one of the pulleys or rollers 21 around 75 which the apron 6 passes, normally run on the ground. The hood is open at its rear, Fig. 5, and its walls, while straight, taper or are inclined toward its front as clearly shown in that figure. The apron extends 80 sidewise at the front of the hood as shown in dotted lines in Fig. 5. The apron 6, and broom 4, are of substantially the same width as is also the opening at the back of the hood. Sweepings leaving the broom are received into the open end of the housing and are gradually collected toward the center of 85 the machine by the straight side walls of the housing which start from the ends of the broom and gradually approach each other 90 and since the apron 6, is of the full width of the broom and of the inlet of the housing it operates in connection with the straight but approaching side walls to carry forward any sweepings and thus keep the housing clear 95 of the accumulation of sweepings. The yoke 22 which is connected with an arm on the cross-shaft 23 serves as a means for lifting the comb and parts connected therewith clear of the ground. To the shaft 23 is connected an arm 24 and to this arm 24 is connected a chain 25 which is attached to a lever 26 that serves to lift the comb, the latter being connected to the yoke 22 and shown as being pivotally mounted. There is a shaft 100 27 revolvably mounted in the frame, or more accurately, in brackets carried thereby, and this shaft is driven, as shown, by a sprocket chain 28 from the rear axle 29 which turns with the rear wheels. 105

30, is a clutch shifted into one position by the spring 31 and into the other position by

a bell-crank 32 and link 33, a lever 34 and a chain 35 attached to a handle 36 so that by operating the handle 36 the clutch can be shifted against its spring 31 in order to 5 make the sprocket drive operative or inoperative. The shaft 27 by gear wheels 37 drives the shaft 38 and there is a sprocket wheel on the shaft 38 which by means of a sprocket chain 39 drives a sprocket wheel 10 on the broom shaft and thus the broom is revolved. The shaft 38 drives the shaft 40 which is journaled in the frame, or more accurately in brackets connected therewith, by means of the sprocket chains and wheels 15 41. The shaft 40 is at the boot of the elevator and it is provided with the sprocket wheels 42 which drive the latter. The shaft 40 by means of gear wheels 43 drives the roller 44 around which the apron 6 passes so that 20 the apron itself is driven. The various guide rolls 45 for the elevator are mounted in brackets 46 that are carried by the frame of the machine.

The body 10 is of the self-dumping 25 variety. It is provided with hinge members 47 and they are pivoted to the rails 1 by a rod 48, the purpose of this pivotal connection is to prevent end-wise movement of the body in respect to the frame and to 30 permit the body to dump, which it does by reason of chairs 49 which rest on the angle frames 1 between the flange of the angle irons and clips 50 secured thereto. When the wagon is dumped the chair turns about 35 its rear edge, which is aligned with the rod or pivot 48, and the rear end of the chair abuts on the inclined surface 51 at the end of the rails 1, forming a stop. In turning the body is carried by the rear edge of the 40 chair rather than by the pivot 48. When the body is loaded its load is so distributed that it tends to turn and dump. The latch 52 serves to prevent the body from dumping. The latch is centrally pivoted and one 45 end is operated on by the spring 53. The other end is connected by a chain 54 with the foot lever 55, so that when the lever 55 is pushed the latch releases the body; that is, its lower end slips off the front end of the

body. The chute 9, when the body is 50 dumped, may turn into the position indicated in Fig. 2, there being a suitable opening in the top of the body for the chute to enter.

The tail-board 56 is carried by arms 57 55 centrally pivoted to the body. Links 58 connect these arms with other arms 59 pivoted to the frame and the arms 59 are connected by links 60 with the body so that when the body dumps the tail-board occupies 60 the position shown in Fig. 2. After dumping, the body is returned to its initial position by arms 61 pivoted to the frame, or more accurately to the bolster of the rear axle. These arms are connected by links 62 65 to the arm 63 on a shaft 64 pivoted to the frame and provided with an arm 65 to which is connected a link 66 that is connected with a lever 67 so that when the lever 67 is pulled the free ends of the arm 61 turn upward and 70 push the body back to its original position.

What I claim as new and desire to secure by Letters Patent is:

A street sweeper comprising the combination of a wheel frame, a comb between the 75 wheels, a straight broom within the wheel base and in rear of the comb, an upright elevator and its boot arranged centrally of the frame, a rearwardly open hood having straight side walls extending from the ends 80 of the broom inward to the entrance of the upright elevator foot, and a traveling apron constituting the floor of the hood and of substantially the width of the broom and projecting at the front outside of the straight 85 side walls of the hood and operating in conjunction with the straight side walls throughout their length to directly receive sweepings and deliver them without accumulation in the hood. 90

In testimony whereof I have hereunto signed my name in the presence of witnesses.

HENRY PEZZETTI.
